UNITED STATES PATENT OFFICE

BENJAMIN A. MORTON, OF NEW YORK, N. Y.

WINDOW CONSTRUCTION

Application filed August 18, 1927. Serial No. 213,729.

This invention relates to window construction and has for its object to provide a window in which the sashes can be securely clamped in place in closed position or any position of adjustment, but may be loosened so as to be freely movable when it is desired to open or close the window.

A further object of the invention is to provide a window of this class wherein the mechanism for holding the window in fixed position extends throughout the entire length of the window and not only makes a tight connection with the window throughout the length of the window, but also tightly engages the window frame and thereby makes the window weather- and wind-proof to an extent impossible with windows operating in fixed guideways and which must therefore be more or less freely movable.

20 A further object of the invention is to provide a window of this character which costs but little more than an ordinary sliding sash window construction, which may be readily installed in houses already built, as well as in new buildings, and which is adaptable to either wooden or metal window frames.

A further object of the invention is to provide a window construction of this character which has no unsightly parts and which in effect is indistinguishable from ordinary sliding sash windows except for the provision of a small operating member which may be a small handle, a thumb screw or similar inconspicuous part. It may be a window of more than two sashes and may be used for the operation of shutters or screens. It may be used for windows in railway or other cars as well as in any type of building. It may be used for windows of one movable pane of glass as in an automobile.

In the accompanying drawings I have disclosed my invention applied to a wooden frame sliding sash window of usual construction.

45 In said drawings,

Fig. 1 is a vertical sectional view through one side of a window frame equipped with my improvement and showing the adjacent portions of the sashes in elevation;

Fig. 2 is vertical section at right angles to Fig. 1, on the line 2—2 thereof;

Fig. 3 is a perspective view partly in section on an enlarged scale of the lower portion of the window;

Fig. 4 is a sectional view on line 4—4 of Fig. 1 showing the parts adjusted to loosen the window so that it may be raised or lowered;

Fig. 5 is a similar view with the parts adjusted to the position for clamping the window tight; and

Fig. 6 is a sectional view on an enlarged scale on line 6—6 of Fig. 1.

Referring to the drawings, 1 is the vertical member of the house wall at one side of the window opening, and 2 and 3 indicate, respectively, the upper and lower sashes forming the window. The sashes 2 and 3 are of a width somewhat less than the space between the member 1 and the corresponding member at the other side of the window so as to allow a free space for the window weights 4. The window frame consists, as is usual, of inner and outer pieces 5 and 6, respectively, which are fastened along one edge to the edges of the wall portion 1, as shown in the several transverse sectional views, the space between the frame members 5 and 6 and the sash frames being taken up with strips 7 and 8, respectively, of a thickness to leave a space on each side for receiving the flanges of the sash guide 9. This sash guide forms one of the principal parts of my invention and consists preferably of sheet metal, such as pressed steel, in the form of a double channel. The sash guide 9 is of a length to extend from the bottom member 10 of the window frame to the top member 11, and the two flanges at the edges of the sash guide extend, respectively, between the spaces between the sash frames and the adjacent strips 7 and 8. The inner faces of these flanges, that is, the faces adjacent the sashes, are inclined or beveled as shown, and the adjacent portions of the sashes are correspondingly beveled so that as the sash guide is forced outwardly or toward the sashes the two sashes will be clamped together. The middle strip 12 may

90 be tapered also, but is preferably flat, so that 100

the sash frames will be drawn toward each other by the clamping action of the sash guide. The guide member 9 is formed of metal sufficiently light and elastic for the flanges to be capable of spreading slightly to thereby clamp against the strips 7 and 8, whereby a weather-tight engagement is formed not only between the sash and the sash guide, but also between the sash guide and the window frame.

Any suitable mechanism may be employed for shifting the sash guides toward and from the sash frames to lock the sashes in position in the manner described. The mechanism shown in the drawing consists of a rectangular sheet metal frame 13 of a length slightly less than the height of the window and with its two vertical members in engagement with the rear face of the sash guide 9 at its edges. The frame 13 is vertically movable and has attached to it a series of rods or bars 14 whose ends are cylindrical, as shown, and project beyond the edges of the frame 13 and the sash guide 9, in position to engage the inclined faces of cam blocks 15 attached to the inner faces of the frame members 5 and 6 adjacent the ends of the bars 14.

Three bars 14 are shown but the number may obviously be greater or less if desired, depending primarily upon the height of the window. The blocks 15 are thicker at the bottom than at the top so that when the frame 13 is lowered it will thrust the sash guide toward the sash frames, and when elevated will permit the sash frames to be withdrawn and thereby free the sashes.

To insure the positive release of the sashes when the frame 13 is raised there is provided, as shown in Figs. 3 and 6, a spring device comprising a bar 16 attached to the back of the sash guide 9 at its middle part and with its ends bent outwardly to clear the frame 13 and extend beyond the frame to thereby provide a space between the ends of the bar and the strips 7 and 8. Each end of the bar carries a cup or spring guide 17 in which is seated a spring 18 working between the bottom of the cup and a plunger 19 whose head presses against the inner face of the strip, whereby the spring will be compressed by the movement of the sash guide toward the sash frames and when released will force the frame outwardly to positively free the sash frames. The extent of movement of the springs is limited by pins 20 in the end of the plungers. Spring bars 16 are provided at both the top and bottom of the window, as shown in Fig. 2, and obviously, of course, other bars may be provided at intermediate points, particularly with high windows.

Any suitable mechanism may be employed for raising and lowering the frame 13. As a convenient device for this purpose I have illustrated a lever 21 fulcrumed at its far end to the inner face of the outer sash frame.

member 5 and projecting through the inner frame member 6 as shown particularly in Figs. 2 and 3. This pivot opening is sufficiently large to give the necessary play in raising or lowering the lever. The lever is pivoted to the bottom cross member of frame 13, and its outer end terminates in a handle 22 whereby it may be readily operated. A block 23 is attached to the lever back of the handle and this block works in a vertical guideway 24 attached to the face of the window frame, the frame 13 being provided with a lock 25 whereby the block 23 is locked in either upper or lower position, as desired.

Instead of block 23 attached to the lever back of the handle there may be a metal guard, closing the opening in which the lever operates and extending under a guideway so as at all times to be under a thumbscrew which may be screwed down so as to hold the lever firmly at any point.

It is of course to be understood that my invention is not limited to the particular devices for operating the frame 13 or the wedge and rod construction for forcing the sash guide toward and from the window sashes. While the mechanism illustrated constitutes the preferred form in which the invention is to be embodied, other mechanical movements may be employed instead, for example, eccentrics pivoted on the window frame pressing against the back of the sash guide might be employed.

As stated above, the sash guide extends from top to bottom of the window and is slotted at the top to receive the edges of the pulleys for the window weights. The flanges at the edges of the sash guide are, however, continuous from end to end, and consequently when the window is closed and the sash guides clamped against the sash rails a weather-tight joint will be formed throughout the length of the upper sash between the sash and the sash guide and also between the sash guide and the window frame. There will also be a weather-tight pressure between the sashes where they overlap and between the inner face of the lower sash and the adjacent flange of the sash guide and the window frame.

A set screw may, if desired, be used instead of the lock 25, but I prefer to use the lock so that the window may be locked at night with the lower sash or upper sash raised for ventilation and at the same time prevent ingress through the window. The grip of the clamping mechanism is such that the sash frame will give way before the window will move, and unless the handle of the lever 21 be positively pressed downward the window will remain locked, for the inclined faces of the blocks 15 are very gradual and under the pressure brought about by the clamping action, the frame 13 will be held in place until positively elevated.

- It will be understood, of course, that it is not necessary to have sash guides at both sides of the windows for adjustment in the manner described. The sash guide at one side may be 5 movable and at the other side may be of the same design but fixed in position whereby the movement of the movable sash guide will force the sash against the fixed sash guide and thereby clamp the sashes at both edges.
- 10 When so constructed, spring buttons may be inserted in the fixed sash guide to release the window when pressure on the opposite side of the sash is released. When two movable sash guides are employed they may be coupled 15 together by any suitable mechanism for operation from a single lever.

While I have described my improvement as applied to the sides of the window frame, a similarly movable channel may be provided 20 to receive the top of the upper sash and bottom of the lower sash when the window is closed, to thereby clamp the window around its entire edge and make it substantially airtight. Such additional channels are, however, not necessary, as ordinary tongue-and-groove metal weather stripping makes a sufficiently tight joint at the top and bottom of the window for all practical purposes. Such 25 weather stripping is not, however, satisfactory at the side edges of the window for the reason that if the engagement is tight enough to keep out the weather it makes the window 30 too tight to open and close freely.

I claim:

35 1. The combination in a window of a window frame, a sash movable therein, a guide for said sash, and means for clamping said guide against said sash and simultaneously against said frame to make said sash immovable and said window weather-tight.

40 2. In a window the combination of a frame, a plurality of movable sashes therein a guide extending the full length of said frame, and means for clamping said guide against said sashes and against the frame throughout the 45 length of the window to thereby render said sashes immovable and the window weather-tight.

50 3. In a window the combination of a frame, a sash movable therein, a guide for said sash comprising a channel member mounted for movement in said frame toward and from the sash, and an inclined face on one of said parts 55 and adapted upon movement of the guide member toward the sash to cause the flange of the channel member to be clamped against the sash and against the frame and render the same immovable.

60 4. In a window the combination of a frame, a sash movable therein, a guide for said sash comprising a channel member having its flanges capable of slight spreading without permanent distortion mounted for movement 65 in said frame toward and from the sash, and

an inclined face on one of said parts whereby movement of the guide member toward the sash causes the flange of the channel member to be clamped against the sash and render the same immovable.

70 5. In a window the combination of a window frame, a sash movable therein, a guide for said sash adjustable toward and from the sash to clamp the same against movement and means for adjusting said guide comprising a stationary cam attached to the window frame and a cooperating part movable with respect to said cam and engaging said guide to move the same toward the sash on movement of the operating member with respect 75 to the cam.

76 6. In a window the combination of a window frame, a sash movable therein, a guide for said sash extending the full length of said window and adjustable toward and from the sash to clamp the same against movement, and means for adjusting said guide comprising a plurality of stationary cams attached to the window frame adjacent said guide at different points in its length, an 80 adjustable part extending substantially the length of said guide and having portions cooperating with said cams, said part engaging said guide and adapted upon movement of said part relative to said cams to shift said guide against said sash and lock the same 85 against movement.

90 7. In a window the combination of a window frame, a sash movable therein, a guide for said sash adjustable toward and from the sash to clamp the same against movement and means for adjusting said guide comprising a stationary cam attached to the window frame, a cooperating part movable with respect to 95 said cam and engaging said window guide to move the same toward the sash on movement of the operating member with respect to the cam, an operating member connected to said part having a handle projecting beyond said frame, and means for locking said member against movement.

100 8. In a window the combination of a frame, a plurality of movable sashes therein, a window guide extending the full length of said frame, means for clamping said guide against said sashes throughout the length of the window to thereby render said sashes immovable and the window weather-tight, and springs arranged to normally hold said 105 guide away from said sashes to allow the sashes to be freely movable.

110 9. In a window the combination of a frame having a channel therein, a plurality of sashes movable in said channel, said channel being a width greater than the thickness of the two sashes, a window guide mounted in said channel having flanges projecting between the walls of said channel and the frames of the sashes, means for moving said 115 120 125 130

guide toward and from the sashes and co-operating inclined faces on two of said parts whereby movement of the guide toward the sashes causes the flanges of the guide to be clamped against the sashes and also against the adjacent face of the window frame.

In testimony whereof I affix my signature.
BENJAMIN A. MORTON.
